US0D1094444S

(12) **United States Design Patent** (10) **Patent No.:** **US D1,094,444 S**
(45) **Date of Patent:** **** Sep. 23, 2025**

(54) **DISPLAY SCREEN OR PORTION THEREOF
WITH A GRAPHICAL USER INTERFACE**

(71) Applicant: **Snap Inc.**, Santa Monica, CA (US)

(72) Inventors: **Devin Doty**, Brooklyn, NY (US); **Ian Anthony Wehrman**, Venice, CA (US)

(73) Assignee: **Snap Inc.**, Santa Monica, CA (US)

(**) Term: **15 Years**

(21) Appl. No.: **29/784,445**

(22) Filed: **May 19, 2021**

(51) LOC (15) Cl. **14-04**

(52) U.S. Cl.

USPC **D14/485**; D14/488

(58) **Field of Classification Search**

USPC D14/485-495

CPC G06F 3/048-04897

CLAIM

The ornamental design for a display screen or portion thereof with a graphical user interface, as shown and described.

DESCRIPTION

The FIGURE is a front view of a display screen or portion thereof with a graphical user interface, showing our new design.

The broken lines illustrate the display screen, and the broken lines form no part of the claimed design.

1 Claim, 1 Drawing Sheet
